(No Model.)

H. H. WHITCOMB.

TOY PISTOL.

No. 247,283.

Patented Sept. 20, 1881.

Fig. 1.

UNITED STATES PATENT OFFICE.

HENRY H. WHITCOMB, OF BRIDGEPORT, CONNECTICUT.

TOY PISTOL.

SPECIFICATION forming part of Letters Patent No. 247,283, dated September 20, 1881.

Application filed April 8, 1881. (No model.)

To all whom it may concern:

Be it known that I, HENRY H. WHITCOMB, of Bridgeport, in the county of Fairfield and State of Connecticut, have invented certain new Improvements in Toy Pistols; and I do hereby declare that the following is a full, clear, and exact description of the invention, which will enable others skilled in the art to which it appertains to make and use the same.

10 The object of my invention is to construct a toy pistol, used for exploding paper caps and blank cartridges, with suitably-arranged movable figures operated and controlled by the works of the pistol.

15 My invention consists of a figure hinged at or near the end or muzzle of a toy pistol, controlled and operated by the works, preferably the hammer, so arranged that when the hammer is raised the figure will be made to assume

20 a perpendicular position, and when the hammer explodes the cap or cartridge the figure, with a simultaneous movement, will fall and assume a horizontal position.

25 My invention further consists in providing a spring-catch to be placed on the barrel of the pistol, so constructed and arranged that when the hammer falls and explodes the cartridge it will lock and prevent recoil.

30 To more clearly understand my invention, reference is had to the drawings accompanying this specification and forming a part thereof, in which—

Figure 1 represents a view of a toy pistol for exploding blank cartridges:

35 A is an auxiliary barrel in which the cartridges are placed, and is mounted on the top and connected to the barrel B.

40 C is the figure of an Indian, mounted on the block D, which oscillates on the pin a, passing

45 E is an extension of the barrel B, open at the top to admit the figure C, as shown more clearly at Fig. 2, which represents a section of the barrel B, showing a top view of the barrel B and open extension E, (the figure C removed,) showing the pin a, on which the figure swings, which passes across the extension E and has its bearings in the ears b b.

50 c (see Fig. 1) is the rod for operating the figure. One end is connected to the block D, on which the figure is mounted. The other end, 1, engages with the corner 2 of the hammer F.

d is a spiral spring on the rod c, which throws the figure down when the hammer is released. The spring d may be dispensed with by passing the pin a through the block D, forward of the figure C, which will cause the figure to fall by its own weight. 55

e is a collar attached to the rod c, against which the spring acts. 60

f f' are partitions or ribs within the barrel B, to guide the rod c.

On top of the auxiliary barrel A is the catch-spring g, one end attached to the barrel A by the rivet h, the other end overhanging and provided with the catch i, which engages with the projection j of the hammer F, which operates to prevent a recoil of the hammer when the cartridge is exploded, thus avoiding accidents by the shells being blown back. 65

k is a guard over the spring g, to prevent side-play and keep it in place, and sufficiently high to allow a free upward movement of the spring to enable the hammer to pass under the catch in its downward movement. 70

Fig. 3 is a view of the end of the barrel A, showing the catch-spring and guard k.

Its operation is as follows, (see Fig. 1:) When the figure is down and in the extension E the end 1 of the rod c will rest on the perpendicular face G of the hammer F. Raising the hammer forces the rod forward until the end 1 of rod c rests on the point 2 of the hammer, compressing the spring d and raising the figure C, having its bearing on the pin a, to an upright position. 85 On releasing the hammer to explode the cartridge the spring d expands, acting against the collar e, swinging the figure C to a horizontal position, its downward movement indicated by the dotted line and arrow. The hammer in its downward movement comes in contact with the catch i of the spring g, which is sufficiently elastic to give way to the force of the hammer. The catch i will engage with the projection j of the hammer, locking it securely and preventing recoil. In cocking the pistol, the spring g must be raised sufficiently to release the catch. 90

The spring d on the rod c can be used, if necessary, to explode the cap or cartridge, in place of the spring usually employed in pistols for operating the hammer. 95

Having thus described my invention, what I claim as new, and desire to secure by Letters Patent, is—

1. In a toy pistol, the figure C, placed at or near the muzzle, said figure operated and controlled by the hammer F and rod c, so arranged and constructed that when the hammer is raised it will engage with the rod c and raise the figure to an upright position, and when the hammer is released the figure will assume a horizontal position and disappear within the extension E, having open top attached to and projecting beyond the muzzle, substantially as set forth.
2. The combination of the figure C, block D, pin a, having bearings in the ears b b, rod c, spring d, and collar e, with the hammer F, as set forth.
3. The combination, with the chamber A and hammer F, of the spring g, guard k, and catch i,

to engage with the notch or projection j of the hammer F, whereby the hammer is locked to prevent recoil, substantially as set forth.

4. The barrel B, having chamber A to receive caps or cartridges, in combination with the hammer F and mechanism within the barrel B to operate the figure C, consisting of the rod c, spring d, and block D, substantially as described, and for the purpose set forth.

In testimony that I claim the foregoing I have hereunto set my hand this 5th day of April, 1881.

HENRY H. WHITCOMB.

Witnesses:

HERMAN GAUSS,
RUDOLPH KOST.
